UNITED STATES PATENT OFFICE.

HENRY T. HARTMAN, OF NEW YORK, N. Y.

DENTAL BRUSH.

Specification of Letters Patent. Patented Feb. 20, 1917.

1,216,311.

Application filed November 29, 1916. Serial No. 134,047.

To all whom it may concern:

Be it known that I, HENRY T. HARTMAN, a citizen of the United States, residing in the borough of the Bronx of the city of New York, in the State of New York, have invented certain new and useful Improvements in Dental Brushes, of which the following is a specification, reference being had to the accompanying drawings, forming a part thereof.

The object of this invention is to provide a rotary dental brush which is extremely simple in construction, inexpensive to manufacture and susceptible of general use without the exercise of any skill on the part of the user. A further object of the invention is to construct a brush of the type noted which shall be highly sanitary and permit, by simple manipulation, the dismembering of certain of its parts for the removal or cleansing thereof. A further object of the invention is to provide an improved brush which may be used with the device for rotating it which brush is inexpensive to construct and easily cleaned either while in operating position or when removed from the operating mechanism, or which may after use be thrown away, sanitation being assured thereby. Other objects of the invention will appear in connection with the description of the accompanying drawings, in which is illustrated the preferred form of the invention.

In the drawings—

Figure 1 is a view in perspective of the improved brush, a part of the casing for the shaft being broken away to show details of construction.

Fig. 2 is an enlarged detail view, mostly in section, of the brush proper and the means for clamping the brush in position.

Fig. 3 is an end view of the brush showing the relation of the guard thereto.

Figs. 4, 5 and 6 are detail views of the brush proper showing it in different stages of formation.

It is essential in a device of this character that the construction shall be as simple as possible, so that it may be inexpensively manufactured and sold and may also be used generally by persons who have no mechanical skill. To this end, the number of parts have been reduced as much as possible and these parts are associated with each other by securing means which perform their intended functions in a manner which will be evident to the most unskilled user upon observation.

As shown in Fig. 1, the handle *a* of the brush which may be grasped by the user is formed as a tube in which is mounted the actuating shaft *b*, on one end of which is secured a bevel pinion *c* adapted to mesh with an actuating master gear *d* which is journaled in the tube *a* and is formed with a suitable handle *d'* to facilitate manual operation. The stud *d*² on which the gear is carried passes through the wall of the tube *a*, and with an annular crimped section *a'* of this tube constitutes an abutment to hold the shaft *b* against axial movement. This annular abutment *a'* rests within an annular groove *b'* formed in the shaft so that the edges of the groove will remain in constant engagement with the sides of the abutment and the shaft be held against movement. The freed end of the rotative shaft *b* projects beyond the end of the tube *a* and carries suitable devices for holding the bristles of the brush. As shown in Fig. 2, this end of the shaft *b* may have formed integral therewith or, as in the illustrated embodiment, have threaded thereon a tapered section *e* in which is formed an axial recess *e'* to receive a compression spring *f* for a purpose which will appear. The end proper of the shaft *b* is also recessed, as at *b*², to afford a bearing for a plunger *g* which projects beyond the end of the brush and affords a bearing section which is brought into engagement with a tooth for the purpose of maintaining the brush conveniently in the desired position during use. This plunger *g* carries a flange *g'* on which bears the spring *f*, the other end of the spring being seated against the flat end of the shaft *b*. From this description it will be understood that the plunger *g* when brought into engagement with a tooth is pressed outward yieldingly so that some range of play for the brush over the tooth is allowed. As shown in Fig. 2 the tip of the plunger may be covered with some resilient material, such as rubber, indicated at *g*², to afford a pleasant cushioned seat.

Before proceeding with the details of the clamping means for holding the bristles in position, it might be well to refer to Figs. 4-6 for an explanation of the brush structure proper. This brush may be made up out of a plain corrugated sheet of relatively stiff but flexible paper board *h* or the like, the inner surface of which is formed with transverse corrugations *h'* in which may rest the tufts of bristles *i*. After the bristles have been positioned in these corrugations a flexi-

ble wire k may be laid lengthwise of the paper back h across the bristles along a line at about their mid-section and the paper then bent with the bristles about the wire k to some such position as is indicated in Fig. 5. The ends of the wire k , as shown in Fig. 4, may then be bent around the back of the paper h or twisted together for the purpose of holding the bristles permanently in position. The brush thus formed may be marketed conveniently and sold very cheaply to users of the improved actuating mechanism. This brush, while flat when purchased, may be placed in the machine and held about the circular tapered portion e of the shaft so as to form an annular brush of the character indicated in Fig. 3. To this end, the tapered portion e of the shaft b is shouldered, as at e^2 , near its end face, and the wire k of the bristles is passed around the tapered portion under this shoulder e^2 until the brush assumes a generally circular form. The brush is clamped in this position by means of a circular conical hood l which is in threaded engagement with the tapered section e of the shaft and may be backed off this tapered portion and slid loosely along the shaft b to such position as will permit the brush h to be placed about the conical section e . When this clamping hood is moved forward and threaded on the tapered section e , its flaring sides will engage the backing portions of the brush h and press them firmly against the annular shouldered portion of the conical section e . In this position, the bristles will be firmly clamped in place and held securely against movement. The conical clamp l is locked against axial movement when once positioned by means of a suitable spring latch m carried on the shaft b and arranged to engage a longitudinal slot l' in the end of the hood l . This latch m , may of course be tripped by the finger so as to permit the hood to be backed off the conical section e .

The improved brush may be provided with a suitable guard n whereby the mucous lining of the mouth may be protected against the rotating bristles at such time as the brush is to be employed only on limited areas of the sides of the teeth. This guard n may be of any desired shape, although the form shown in the drawings will probably be the most useful. In this form the guard is arcuate and lies over a portion of the bristles at an angle somewhat less than 180° . This guard may be supported on the tube a by means of a spring clip n' by which the guard may be adjusted to any desired position and held yieldingly on the tube.

In use, when the improved brush h is to be clamped in position in the manner de-

scribed, the latch m will be pressed in by the finger and the clamping hood l backed off the conical section e so as to permit the wire k of the brush to be placed in position behind the shoulder e^2 on the flaring end of the shaft. When thus positioned the hood l is slid forward on to the conical section until the brush h is firmly clamped in place and the latch m engaged with its coöperating notch. Any form of dental cream or powder may be placed on the bristles in the usual manner and the rest g^2 brought into engagement with a tooth at about the section where the brush is to be applied. Rotation of the handle d' , by reason of the high gear ratio, will serve to rotate the annular brush at a very high speed so that the usual slow reciprocations of the flat bristle brush are replaced by the high speed wiping action of the projecting bristles of the improved brush in much the same way used by dentists. Further, the character of the brush h is such that the bristles may be caused to penetrate between the teeth even at the more troublesome sections of the mouth and effectively remove all deposits thereon.

It is evident that brushes of other forms and composition may be substituted, or a polisher of rubber may be used in much the manner employed by dentists.

Changes in design and details of construction may be made without departing from the spirit of the invention provided such departures fall within the scope of the appended claims.

I claim as my invention:

1. A rotary dental brush including a rotatable shaft, gearing to impart rotation to the shaft manually, a rotary brush carried on the end of the shaft, a circular clamp threaded on the end of the shaft and movable axially into and out of engagement with the brush to lock it releasably in position and a plunger mounted yieldingly in the end of the shaft to engage the teeth and serve as a rest for the brush.

2. A rotary dental brush including a rotatable shaft, a conical section threaded on its end, gearing to impart rotation to the shaft manually, an annular shoulder formed adjacent the end of the conical section, a circular brush disposed about the conical section and engaged with the shoulder, a conical sleeve threaded on the conical section and movable into and out of engagement with the brush for clamping it releasably in position, and a spring latch engaged operatively with the conical sleeve for holding it against axial movement.

This specification signed this 27 day of November 1916.

HENRY T. HARTMAN.
